United States Patent Office

Des. 214,823

Patented July 29, 1969

214,823

ELECTRIC SHAVER

Ronald L. Seymour, Hometown, and Gordon T. Guth,
Evanston, Ill., assignors to Sunbeam Corporation, Chi-
cago, Ill., a corporation of Illinois

Filed July 12, 1968, Ser. No. 12,729

Term of patent 14 years

Int. Cl. D28—03

U.S. Cl. D95—3

FIG. 1 is a front perspective view of an electric shaver showing our new design;

FIG. 2 is a top plan view thereof;

FIG. 3 is a bottom plan view thereof;

FIGS. 4 and 5 are left and right end elevational views, respectively; and,

FIG. 6 is a rear elevational view thereof.

We claim:

The ornamental design for an electric shaver, as shown.
